UNITED STATES PATENT OFFICE.

EUGENE S. BROWN, OF OAK STATION, PENNSYLVANIA.

DESIGN FOR A GAS HEATER.

Application filed March 8, 1924. Serial No. 8,872. Term of patent 14 years.

To all whom it may concern:

Be it known that I, EUGENE S. BROWN, a citizen of the United States, residing at Oak Station, in the county of Allegheny, State of Pennsylvania, have invented a new, original, and ornamental Design for Gas Heater, of which the following is a specification, reference being had to the accompanying drawing, forming a part thereof.

The figure is a perspective view of a gas heater, showing my new design, a portion of the radiants being indicated by full lines, and the remainder indicated conveniently by dotted lines.

I claim:

The ornamental design for a gas heater, as shown.

EUGENE S. BROWN.
